**GUIDE FOR SEWING DECORATIVE MATERIAL
TO BASE MATERIAL**
Angelo Micale, 995 Nassau St., North Brunswick, N.J.
Filed Oct. 22, 1963, Ser. No. 318,032
1 Claim. (Cl. 112—151)

This invention relates to a guide for sewing decorative material to a base material.

An object of the invention is the provision of a tubular guide for decorative material as it is being sewed onto a base material, which guide is adjustable to the width of the decorative material and which may be disposed at various angles from a vertical to a horizontal position, and it is also adjustable vertically, laterally, and forward and backward, relative to the foot.

Another object is the provision of an edge guide for the base material on which a decorative material is being sewed, which edge guide is adjustably connected to the tubular guide above mentioned.

The drawings illustrate the invention, and in these:

FIG. 1 is a front view of the device attached to the foot bar of a sewing machine, with a foot depending from the foot bar;

FIG. 2 is a side view of FIG. 1;

FIG. 3 is a plan view of a tube forming part of FIGS. 1 and 2 and holding within it a pair of adjustable guides;

FIG. 4 is a side view of FIG. 3;

FIG. 5 is a front elevation of the tube of FIGS. 3 and 4;

FIG. 6 is a bottom plan view of the tube of FIGS. 3, 4, and 5;

FIGS. 7, 8 and 9 are respectively bottom plan, front, and side views of the foot shown in FIGS. 1 and 2 as attached to the foot bar;

FIGS. 10 and 11 are respectively side and plan views of a bar which swivelly connects to the tube;

FIG. 12 is a section on line 12—12 of FIG. 1; and

FIG. 13 is a section on line 13—13 of FIG. 1.

Referring to the drawings for a detailed description, the numeral 17 indicates a flat, elongate tube through which decorative material passes just before being sewed onto a base material. The tube is shown, in FIGS. 1 and 2, and in the vertical position, in which the decorative material comes down vertically from above the tube, and after passing through it, turns forwardly to pass under the foot 19, the tube being held above the functional part of the foot as shown in FIGS. 1 and 2. The foot, as usual, is secured to the pressure foot bar 20.

To guide different widths of decorative material through the tube, a pair of similar, adjustable guides 22 pass vertically through the tube, and are separately movable lengthwise thereof. Each guide (FIG. 13) is in two connected but separable parts, viz., a lower part 25 which is externally threaded at its upper end portion, and a hollow, internally threaded, upper part 26 which threadedly connects with the lower part and constitutes a thumbscrew. The lower part extends upwardly through the tube and has an enlarged lower end 27, which end abuts a lower internal shoulder 28 formed in the tube 17. The thumbscrew 26, when tightened, abuts an upper internal shoulder 29 formed in the tube 17. When the movable guides are properly placed and tightened in the tube, the

2

decorative material to be sewed onto a base material moves through the tube between the guides.

The tube 17 may be moved to any position from the vertical to the horizontal, being swivelly connected, at its right hand end, by a screw 32, to one end of a right-angle connecting bar 33 (FIGS. 1, 2, 10 and 11). This bar extends rearwardly from its point of connection with the tube 17, and at its angle turns left, parallel with the tube, to be adjustably fastened to a clamping connector 35 (FIG. 2). The connector 35 is fastened to the pressure foot bar 20 of the machine, being adjustable angularly relative thereto, so that the tube 17 may be adjusted to a desired height above the foot 19. The connector 35 receives, near its rear end, the bar 33, and is there split. A screw 37 (FIG. 2) passes through the split end position and tightens the bar in a desired lengthwise position to the connector 35, the tube thereby being adjustable to the right or left relative to the foot 19. The connector 35 has an open slot at its lower end (FIG. 2) through which it receives a fastening bolt to adjustably connect it angularly, and also forwardly and backwardly, to the foot bar.

The tube 17 is sometimes used in the flat position, in which position its front face of the vertical or upright position becomes the bottom, which then rests on the table and in front of the foot. For such position, a guide 40 (FIGS. 1 and 12) is adjustably secured to the bottom of the tube, as positioned in FIG. 1, and serves to guide the right hand edge of the base material, and is called a goods guide. Guide 40 is elongate and has a slot 41 lengthwise of its main portion to receive a threaded bolt 43 (FIGS. 1 and 12) which passes through aperture 44 (FIGS. 5 and 6) in a corner of the tube. The goods guide, adjoining the slot, is channel-shape. A nut 45 (FIGS. 1 and 12) engages bolt 43 and, when tightened, presses against the bottom of the channel. Guide 40 includes an end portion 40A (FIG. 1) which is at right angles to the slotted portion of the guide, and has a straight edge for guiding the base material when correctly positioned relative to the length of the guide.

The foot 19 is secured to the foot bar 20 of the machine; it has an eye 46 and a lateral projection 47 which prevents the marginal portion of the base material from curling up. The foot 19 is not split, as the usual sewing machine foot is. In front of the opening 46 for the needle, it has a rising finger guard 50, from one end of which guard the anti-curling projection extends, as shown in FIGS. 1, 2, 7, 8 and 9.

50 What is claimed is:

A sewing machine attachment comprising a tube having parallel inner faces, a pair of guides through and beyond the tube and separately slidably laterally therein to form between them a channel for the passage of decorative material to be sewed on to a base material, an angular bar to which the tube is swivelly connected to allow a tube to be moved from a vertical to a horizontal position, connecting means for clamping said bar to a sewing machine foot bar, said connecting means allowing said angular bar to be adjustable lengthwise to allow the tube to be shifted to the right or left, said connecting means further providing angular adjustment of said angular bar about an axis perpendicular to said foot bar to allow the tube to be moved up and down, said connect-

ing means being still further operative to secure said angular bar to the foot bar for forward and backward movement to move the tube forwardly and backwardly relative to the foot bar, and a goods guide for guiding a base material, said goods guide being adjustably and 5 slidably secured to and on an outer face of the tube so as to be movable laterally thereto, said goods guide being secured to the outer face of said tube which is the bottom face when the tube is in the flat or horizontal position, 10 said goods guide being separately adjustable with respect to said pair of guides.
